(57) **CLAIM**

The ornamental design for an induction unit for a cooking system as shown.

DESCRIPTION

FIG. 1 is a perspective view of an induction unit for a cooking system in accordance with our design.

FIG. 2 is a top view thereof.

FIG. 3 is a left side view thereof.

FIG. 4 is a right side view thereof.

FIG. 5 is a left side view thereof.

FIG. 6 is a rear view thereof; and,

FIG. 7 is a front view thereof.

The evenly-spaced broken lines shown in the figures depict portions of the induction unit for a cooking system that form no part of the claimed design. The dot-dash lines shown in FIG. 3 depict a boundary line and form no part of the claimed design.

1 Claim, 5 Drawing Sheets
